(57) **CLAIM**

The ornamental design for a clothing care machine, as shown and described.

DESCRIPTION

FIG. 1 is a front perspective view of a clothing care machine, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion 8 in FIG. 1;

FIG. 9 is an enlarged view of the encircled portion 9 in FIG. 1;

FIG. 10 is an enlarged view of the encircled portion 10 in FIG. 2;

FIG. 11 is a perspective cross-sectional view thereof, taken along line 11-11 in FIG. 2;

FIG. 12 is a perspective cross-sectional view thereof, taken along line 12-12 in FIG. 2;

FIG. 13 is an enlarged view of the encircled portion 13 in FIG. 11; and,

FIG. 14 is an enlarged view of the encircled portion 14 in FIG. 12.

The even-dash broken lines illustrating portions of the clothing care machine form no part of the claimed design. The dot-dot-dash broken lines encircling enlargement portions of the claimed design form no part of the claimed design. The dot-dash broken lines in FIG. 2 depict the
